UNITED STATES PATENT OFFICE.

ELMER A. HUNSAKER, OF LINDSAY, CALIFORNIA.

MUSIC-RACK.

1,086,179.

Specification of Letters Patent.

Patented Feb. 3, 1914.

Application filed May 26, 1913. Serial No. 769,975.

To all whom it may concern:

Be it known that I, ELMER A. HUNSAKER, a citizen of the United States, residing at Lindsay, in the county of Tulare and State 5 of California, have invented certain new and useful Improvements in Music-Racks, of which the following is a specification, reference being had to the accompanying drawings.

10 This invention relates to new and useful improvements in music racks and more particularly to an adjustable music rack whereby the music may be held at any desired angle according to the position of the instrument, the object of the invention being to provide a music holder which is readily applicable to the body of an instrument so that the same may be supported in position to hold the music where it can be readily seen 20 by the player.

Another object of the invention is to provide a music holder of the above character which will possess advantages in points of efficiency and durability, is inexpensive of 25 manufacture and at the same time is simple in construction and operation.

With the above and other objects in view, this invention consists in the novel features of construction and the combination and arrangement of parts to be hereinafter more 30 fully described, pointed out in the claim and shown in the accompanying drawings, in which—

Figure 1 is a top plan view illustrating 35 the application of my improved music rack; Fig. 2 is a side elevation; Fig. 3 is a longitudinal sectional view taken through the movable clamping member; Fig. 4 is a transverse sectional view taken through one of the 40 joints which connect the various parts.

Referring more particularly to the drawings, 1 indicates the body or supporting plate, the ends of which are curved, as shown at 2, and disposed at right angles to the body portion. Secured to each of the angularly disposed ends are the clamping members 3 and 3'. The clamping member 3 is rigidly secured to one end of the body while the clamping member 3' is adjustably secured by means of the screw bolt 4, said screw bolt being threaded within one end of the body and having its inner end loosely engaged with the body 5 of the clamping member 3'. A head 6 is formed upon the 55 outer end of the screw bolt 4 whereby the same may be readily manipulated to securely

clamp the members 3 and 3' against the body of the guitar.

Pivots secured, as shown at 7, to the body member 1 is a brace arm 8, the outer ends of which are provided with the cork engaging members 9 which are adapted to engage against the side of the instrument to hold the clamping body more firmly to the instrument, the cork carried by the clamping members 9 and 3 and 3' will prevent them from deadening the sound of the instrument. A connecting arm 10 is provided, the outer end of which is formed with a pivot connection, as shown at 11, and which 60 comprises the two oppositely disposed members 12 and 13 which are suitably connected by means of the rivet 14. Arranged between the members 12 and 13 and encircling the rivet 14 is a spring 15 which is adapted 65 to engage the members 12 and 13 so as to prevent the same from readily rotating so that force will have to be applied thereto.

Pivots connected to the arm 10 are the intermediate arms 16 and pivotally secured 70 to the outer ends of the arms 16 are the curved supporting arms 17, the inner ends of said arms being pivotally connected, as shown at 18, to the outer end of one of the arms 16. Pivots secured to the outer 75 ends of the arms 17 are the resilient retaining members 19, the outer ends of which are curved and bent upon themselves to form the spring clasp member 20, beneath which the music is adapted to be engaged to support 80 the same before the player.

It will be readily apparent that the various connecting joints are provided with the coil springs 15 so as to frictionally hold the various parts of the device in their adjusted position and prevent their swinging 90 until force is applied thereto. From this it will be apparent that the device is extremely simple in construction and can be quickly and readily applied to the body of the instrument so as to support the music in such position where it can be easily seen by the 95 player.

It will also be apparent that the device can be manufactured at a comparatively low 100 cost.

While I have shown and described the preferred form of my invention, it will be obvious that various changes in the details of construction and in the proportions may 110 be resorted to for successfully carrying my invention into practice without sacrificing

any of the novel features or departing from the scope of the appended claim.

What I claim is:—

A device of the class described including a body member, clamping members carried by each end of the body, and adapted to engage an instrument, a brace member pivotally secured to the intermediate portion of the body and adapted to engage the side of an instrument, cork engaging members secured to the outer ends of the brace member, a connecting member pivotally secured to the outer end of the body member, intermediate arms pivotally secured to the connecting member, curved supporting arms pivotally connected at their inner ends to the outer end of one

of the intermediate arms and clasp members pivotally secured to the outer ends of the supporting arms, a joint between the connecting member and the intermediate arms comprising oppositely disposed cup-shaped members, a rivet connecting said members and a coil spring arranged between the members to frictionally engage the same and prevent rotation thereof until force is applied. 20 25

In testimony whereof I hereunto affix my signature in the presence of two witnesses.

ELMER A. HUNSAKER.
